UNITED STATES PATENT OFFICE.

GEORGE J. IRSCH, OF CHICAGO, ILLINOIS.

PAINT-PACKAGE.

1,178,725.

Specification of Letters Patent.

Patented Apr. 11, 1916.

Application filed March 21, 1913. Serial No. 755,877.

To all whom it may concern:

Be it known that I, GEORGE J. IRSCH, a citizen of the United States, residing at Chicago, in the county of Cook and State of Illinois, have invented certain new and useful Improvements in Paint-Packages, of which the following is a specification.

The object of this invention is to produce an improved paint package having the characteristics hereinafter set forth.

In the accompanying drawings, Figure 1 is a top plan view of my improved package. Fig. 2 is an underside view thereof, and Fig. 3 is an enlarged transverse section through the package.

The package comprises the usual base 5 of glass or other suitable material upon the upper surface of which a quantity of paint 6 is deposited. A covering 7 of celluloid 20 or the like rests on said upper surface of the base with its edges, in the present instance, substantially coincident with the edges of the base. The central portion of the celluloid is formed in the shape of a dome which covers the deposit of paint. As will be seen from Fig. 3, the dome of my package is considerably higher than the domes of packages previously produced. This materially lessens the liability of the 25 dome being pressed into contact with the paint 6 which is, of course, undesirable. In producing a cover with a high dome, difficulty has been experienced in preventing the flat or rim portion of the celluloid from 30 buckling or warping. I have found that this can be effectively prevented by forming a small annular groove 8 in said rim portion. In forming a groove in one face a rib is provided on the opposite face. The celluloid cover and the base are secured together 35 in close contact by means of a sheet metal plate 9 overlying the flat rim of the celluloid cover 7 and having a central opening 10 through which the dome projects. Annular flanges 11 at the edges of the plate extend 40 downwardly along the edges of the base 5. At suitable points, preferably at the corners, these flanges are provided with lugs 45 which are bent to lie along the underside 50 of the base 5, thus securing all of the parts together. The plate 9, flanges 11 and lugs 12 may be stamped from an integral piece of sheet metal.

When the parts are secured together with 55 the lugs 12 underneath the base, the rim of

the celluloid and particularly the groove or rib 8 is clamped in close contact between the plate 9 and the upper face of the base, thus producing an effective seal, so that a package which is approximately air-tight, 60 moisture-proof and dust-proof is obtained. It is not necessary that the package be absolutely air tight. In a package constructed as herein shown, the paint will remain in good condition for a year, which is a much longer 65 time than is necessary under practical conditions.

When the user wishes to use the paint, the lugs 12 are bent away from the base 5 and the plate 9 and the celluloid cover 7 may 70 then be raised from the base, leaving the base with the paint thereon freely accessible to the user. The parts may be quickly and conveniently dismembered and assembled, and the same approximately air-tight pack- 75 age is produced each time the parts are assembled together after the paint has been used. Packages have heretofore been produced which were substantially air-tight, but these packages were arranged to be 80 opened by cutting the celluloid along the edges of the sheet metal. Obviously, when once the package was opened, it could not be again closed in air-tight condition. This 85 is one of the important improvements which my package embodies.

I claim as my invention:

1. A paint package comprising a flat base, a celluloid or like cover having a dome in its central portion and having a flat rim contacting the upper face of said base, a flat plate overlying said rim and said base and extending completely around the same in close contact therewith and having a central opening through which said dome projects 90 upwardly, said rim being clamped between said plate and said base in air-tight contact therewith, and a plurality of lugs on the edges of said plate, said lugs being bent to lie beneath said base and thereby releasably 95 clamp the base and the plate together, the base and plate being capable of ready separation and re-association by manipulating said lugs.

2. A paint package comprising a base, a celluloid or like cover having a dome in its central portion and having a flat rim, said rim having a rib formed therein, a plate overlying said rim and said rib, and having 105 a central opening through which said dome 110

projects, said plate having integral angular flanges at its edges lying alongside the edges of said base, and lugs integral with said flanges and bent to lie along the underside 5 of said base, said lugs being arranged to be withdrawn to permit said plate and cover to be removed from said base.

In testimony whereof I hereunto affix my signature in the presence of two witnesses.

GEORGE J. IRSCH.
